UNITED STATES PATENT OFFICE.

ARTHUR AUDET, OF LOS ANGELES, CALIFORNIA.

DRY CONCENTRATING APPARATUS.

1,075,959.

Specification of Letters Patent. Patented Oct. 14, 1913.

Application filed January 14, 1912. Serial No. 742,057.

To all whom it may concern:

Be it known that I, ARTHUR AUDET, a citizen of the United States of America, residing at Los Angeles, in the county of Los Angeles, State of California, have invented a certain new and useful Dry Concentrating Apparatus; and I do hereby declare the following to be a full, clear, and exact description of the invention, such as will enable others skilled in the art to which it appertains to make and use the same.

This invention relates to dry concentrating apparatus, and it may be said to consist in the provision of the novel and advantageous features and in the novel and improved construction, arrangement, and combination of parts and devices as will be apparent from the description and claims which follow hereinafter.

20 One object of the invention is to provide a novel and improved construction for the apparatus which permits of its being compacted to occupy a small space, which as a whole is comparatively light in weight, and 25 which permits of the parts and devices of the apparatus being quickly and easily assembled or demounted.

30 A further object of the invention is to provide novel and improved apparatus of a high degree of adjustability which renders it available for working efficiently on any of the various sorts of material containing mineral values.

35 A further object of the invention is to provide a novel and improved construction for the riffle board which in use causes it to act to spread the material comparatively evenly thereon and thus prevents a piling up of the material in places where its weight 40 would interfere with the proper gravitational movement of the material and prevent the concentrates from working toward the bottom of the riffles; whereby the riffle board works rapidly and efficiently to accomplish improved results in use and to increase the capacity of the apparatus.

45 A further object of the invention is to provide a novel and improved riffle board having a main channel, groups of channels in which adjacent channels are connected with each other and lead to the main channel, and comparatively large smooth surfaces between the groups of channels; whereby the riffle board is adapted to act to cause 55 the material to spread out and move comparatively quickly from the receiving end

to the delivery or discharge end of the riffle board.

Further objects of the invention are to provide novel and improved apparatus of 30 the nature set forth, which is simple in construction, strong and durable, economical to install, maintain, and operate, and which is adapted to produce superior results in practice.

65 Other objects and the advantages of the invention will be apparent to those skilled in the art from a consideration of the following description of the preferred form of construction embodying the invention, 70 taken in connection with the accompanying drawings, in which—

Figure 1 is a perspective view of the apparatus; Fig. 2 is an enlarged partly broken and sectional view of the apparatus taken 75 on the line 2—2 of Fig. 1; Fig. 3 is an enlarged partly broken and transverse sectional view of the upper riffle board, taken on the line 3—3 of Fig. 2; Fig. 4 is an enlarged broken and sectional view taken on 80 the line 4—4 of Fig. 2; Fig. 5 is an enlarged plan view of a portion of the mechanism for reciprocating the tables and screens; Fig. 6 is a sectional view taken on the line 6—6 of Fig. 5; Fig. 7 is a sectional view 85 taken on the line 7—7 of Fig. 6; Fig. 8 is a perspective view of the upper riffle board and of the lower riffle board mounted thereon; Fig. 9 is a perspective view of the upper and lower tables and parts connected 90 therewith; Fig. 10 is a plan view of the amalgamating pan and mounting therefor; Fig. 11 is a sectional view taken on the line 11—11 of Fig. 10; Fig. 12 is a plan view of the lower riffle board; Fig. 13 is a broken 95 longitudinal sectional view of one of the screens; Fig. 14 is a broken plan view of the same, and Fig. 15 is a broken sectional view of the lower riffle board taken on the line 15—15 of Fig. 12.

100 In the several views like characters designate similar parts.

On the preferably rectangular base frame 16 are mounted extensible legs 17 having thereon supporting bars 18 for the table 19. 105 The side members 20 and the end members 21 of the base frame 16 are preferably secured together by plates 22 secured by screws 23 to the members 20 and 21 at the junctions of the members at the corners of 110 the base frame 16. The extensible legs 17 consist of the rods 24 and 25 having adja-

cent ends thereof adapted to screw into adjustable sleeves 26; the parts 24 being connected to the supporting bars 18 by ball and socket joints 28, and the parts 25 being connected to the base frame 16 by having the lower ends thereof adapted to screw into sockets 29 on the plates 22. On the upper side of the supporting bars 18 are mounted runways 30 for the rollers 31 which are 10 mounted on pivots 32 carried on brackets 33 which are suitably secured to the under side of the table 19.

In use, the legs 17 are adjusted to have the top of the table 19 inclined downwardly 15 approximately 22 degrees from the head or receiving end A of the table to the foot or discharge end B of the table, and also to have the top of the table inclined downwardly approximately 8 degrees from the 20 side C to the side D thereof.

Above the top of the table 19 are mounted screens 34 which are arranged one below the other and are of progressively finer mesh. The screens 34 extend the full length 25 of the table 19 and are about one-third the width of the table and are downwardly inclined approximately 30 degrees from the head end A to the foot end B of the table. They are suitably affixed to the frames 35 30 and are each formed to provide a plurality of transverse channels or troughs 36 adapted to hold the larger particles of mineral values and they have their side portions 37 sloping or curved upwardly. The frames 35 35 are adjustably mounted on upwardly extending arms 38 by means of threaded pins 39 suitably fitted in slots 40 in the arms 38; thumb nuts 41 being provided on the pins 39 for securing the frames 35 adjustably on 40 the arms 38.

Below the screens 34 and between the side boards 42 and 43 is arranged the top or riffle board 44 of the table 19, which riffle board has formed on the upper side thereof 45 a series of groups of substantially parallel transverse channels or riffles 45 which in each group are progressively increased in length and connected by gradually offset channels 46; the longer of the channels 45 50 being connected with a comparatively large longitudinal channel 47 which extends along one side of the riffle board to the discharge chute 48. As seen more particularly in Fig. 8, the riffle 45 is formed to provide comparatively large smooth surfaces 49 adjacent to the channel 47 and between the groups of transverse channels 45.

In practice the construction of the riffle board 44 as above described causes the material delivered thereon to be spread out 60 more evenly and moved more rapidly over the riffle board so that the material does not pile up in places and clog or interfere with the desired action whereby the heavier particles find their way to the bottom of the 65

channels 45 and thence to the main channel 47 and to the chute 48 at the end of the main channel. In order to increase the effectiveness of the riffle board 44 in operation, the side 43 which has therein the main channel 70 47 diverges from the opposite side toward the foot or discharge end of the riffle board, and, in order that mineral values may be more certainly caught and held by the riffles 45, the latter are formed with one side portion 51 thereof comparatively shallow and with the other side portion 52 thereof comparatively deep; and openings 53 are formed in the riffle board and lead from the air chest 54 below the riffle board and terminate 75 at the upper end of the sides of the channels 45. Also plates 55 are affixed on the riffle board to have the beveled side portion thereof extending over the edges of the upper ends of the channels 45.

Air under pressure may be supplied to the air chest 54 by means of flexible conduit 58 having one end thereof secured in the opening 56 in the air chest and having the other end thereof connected with the blower 57.

The table 19 is given a smooth and even reciprocation by the mechanism now to be described: the shaft 59 of the blower 57 has thereon a pulley 60 and a pinion 61 in mesh with a spur wheel 62 on the shaft 63 which is preferably mounted on a bearing 64 on the blower 57. The shaft 63 has fast thereon the hollow block 65 in which is slidably fitted the block 66 having thereon the wrist pin 67 and which may be secured in adjusted position in the block 65 by means of set screws 68. An extensible link 69 has one end thereof loosely mounted on the wrist pin 67 and has the other end thereof mounted on a pivot 70 carried by a bracket 71 105 which latter is suitably secured to the underside of the table 19. The length of the link 69 may be adjusted at will by having the parts 72 and 73 of the link adapted to screw into an adjustable sleeve 74.

A lower and smaller table 75 is preferably adjustably arranged at the discharge end of the table 19; the chute 48 being adapted to pass the concentrates from the table 19 to the table 75. It will be understood that one 115 or more screens similar to but of finer mesh than the screens 34 may be arranged on the smaller table 75 to catch the larger particles of the concentrates discharged from the table 19. The table 75 is arranged to have 120 its inclination opposite to the inclination of the table 19, and has its air chest in communication with the air chest of the table 19 through the flexible conduit 76. The table 75 may be adjustably mounted on the 125 table 19 by means of threaded pins 77 on the table 75 which pass through slots 78 in downwardly extending arms 79 which are suitably secured to the table 19; thumb nuts 80 being provided on the pins 77 to clamp 130

the table 75 in adjusted position on the arms 79. The riffle board 81 on the table 75 has the top thereof formed to provide spaced transverse channels 82 connected with a 5 main longitudinal channel 83, a plurality of diagonal channels 83' connecting adjacent channels 82, and comparatively large smooth surfaces 84 adjacent to the main channel 83.

The construction, arrangement, and action of the riffle board 81 is such that when 10 the concentrated material is delivered at the highest point on the head end E of the riffle board, the heavier or valuable particles of the concentrated material move comparatively rapidly through the channels 83', 82 and main channel 83 to the lowest point 86 at the foot or discharge end of the riffle board and thence into the amalgamating pan 87—the lighter or waste particles of 15 the concentrated material moving downwardly over the surface of the riffle board and thence over the edge at the discharge end F of the riffle board.

The amalgamating pan 87 is preferably 20 adjustably mounted on one end of an arm 88 which has the other end thereof mounted on a pivot 89 on the sector plate 90 which is carried by a bracket 91 suitably secured to the under side of the table 75; 25 the arm 88 being provided with an opening whereby a pin 92 may be passed through said opening and through any one of openings 93 in the sector plate to secure the arm 88 adjustably in position on the sector plate. 30 The amalgamating pan 87 may be tiltably mounted on the arm 88 by means of the ball and socket joint 94, and the set screw 95 is adapted to secure the amalgamating pan in 35 adjusted tilted position.

40 While one form of construction embodying the invention has been particularly illustrated and described, there are many changes and modifications thereof that will readily occur to those skilled in the art, wherefore 45 the right is reserved to all such changes and modifications as do not depart from the spirit and scope of the invention as defined in the appended claims.

I claim:

50 1. Apparatus of the class specified, comprising a table, means for movably mounting the table, a riffle board at the top of the table formed with a series of groups of transverse channels progressively of increased length and connected by offset channels, a longitudinal main channel connected 55 with the groups of transverse channels, and

comparatively large smooth surfaces between the groups of transverse channels, and means to reciprocate the table. 60

2. Apparatus of the class specified, comprising a table including an air chest and an inclined riffle board at the top of the table, said riffle board formed with groups of transverse channels progressively of increased length and connected by offset channels, a longitudinal main channel connected with the longer of the transverse channels, comparatively large smooth surfaces between the groups of transverse channels, and openings leading from the air chest and terminating at the top of the sides of said channels, plates affixed on the riffle board and provided with beveled side portions extending over the top edge of the sides of said 75 channels, means for movably mounting the table, and means to reciprocate the table.

3. In apparatus of the class specified, a riffle board formed with a series of groups of transverse channels progressively of increased length and connected by offset channels, a longitudinal main channel connected with the transverse channels, comparatively large smooth surfaces between the groups of transverse channels, said riffle board having 80 openings therethrough terminating at the top of the sides of the channels, substantially as and for the purposes set forth.

4. Apparatus of the class specified, comprising a movably mounted table including 90 an air chest, a riffle board mounted on the table, said riffle board formed with a series of groups of transverse channels progressively of increased length and connected by offset channels, a longitudinal main channel 95 connected with the groups of transverse channels, comparatively large smooth surfaces between the groups of transverse channels, and openings leading from the air chest and terminating at the top of the sides of 100 the channels, plates affixed on the riffle board and provided with beveled side portions extending over the top edges of said channels, means for adjustably supporting the table and means to reciprocate the table. 105

In testimony whereof, I have signed my name to this specification in the presence of two subscribing witnesses at Los Angeles, county of Los Angeles, State of California, this 8th day of January A. D. 1913.

ARTHUR AUDET.
